UNITED STATES PATENT OFFICE.

CHARLES A. HULTQUIST, OF LOS ANGELES, CALIFORNIA.

DRILLING-MACHINE.

1,284,108.

Specification of Letters Patent. Patented Nov. 5, 1918.

Application filed December 28, 1916. Serial No. 139,810.

To all whom it may concern:

Be it known that I, CHARLES A. HULTQUIST, a citizen of the United States, residing at Los Angeles, in the county of Los Angeles and State of California, have invented a new and useful Drilling-Machine, of which the following is a specification.

This invention relates to devices of the character designed to effect turning of a drill steel of fluid-operated tools, such, for instance, as stoping machines, and an object of the invention is to effect such turning of the drill by simple mechanism not liable to get out of order.

Another object is to produce mechanism of this character in which the power impulse for turning the drill will be delivered to the body of the drilling machine with maximum effectiveness.

Other objects and advantages will appear in the subjoined detail description.

The accompanying drawings illustrate two embodiments of the invention:

Figure 1 is a side elevation of a drilling machine embodying one form of the invention whereby oscillation of the drill steel is effected, portions of the drill steel, feed cylinder and handle being broken away to contract the view.

Fig. 2 is an enlarged elevation mainly in mid section of the machine shown in Fig. 1, only a fragment of the body of the machine being shown.

Fig. 3 is a plan section on line indicated by x^3-x^3 , Fig. 2.

Fig. 4 is a plan section on line indicated by x^4-x^4 , Fig. 2, the handle being omitted to contract the view.

Fig. 5 is a plan section on line indicated by x^5-x^5 , Fig. 2.

Fig. 6 is an elevation mainly in mid section of a modified form of the invention, whereby complete rotation of the drill steel is effected.

Fig. 7 is a plan section on line indicated by x^7-x^7 , Fig. 6, the handle being omitted to contract the view.

Fig. 8 is a sectional elevation on irregular line indicated by x^8-x^8 , Fig. 6.

Fig. 9 is a plan section on line indicated by x^9-x^9 , Fig. 6.

There is provided a cylinder 1 having at one end thereof a chuck 2 to hold the drill steel 3 in a manner well understood in the drilling art. The opposite end of the cylinder 1 is provided with a feed cylinder 4 hav-

ing therein a feed piston 5 operated by compressed fluid so as to press the drill against the material to be drilled in a manner well understood in the drilling art. The type of 60 drilling machine shown in Fig. 1 is termed, in the drilling art, a stoping machine, but the features of the invention hereinafter to be described may be used in connection with other types of drilling machines.

The cylinder 1 and feed cylinder 4 constitute the body of the drilling machine and means are provided to turn said body about its longitudinal axis and said means will now be described: The feed cylinder 4, or 70 any other suitable portion of the body, is journaled in a bushing or bushings 6 of bearings 7 which are at opposite sides of a transversely disposed member forming a casing or jacket 8.

Now referring more particularly to Figs. 2 to 5 inclusive, surrounding the feed cylinder 4 within the jacket 8 is a collar 9 having a slot 10 so as to allow said collar to expand and to be contracted by a bolt 11 in 80 order to clamp said collar tightly in place between the opposing ends of the bearings 7, said collar and bearings thus preventing end play of the body 1, 4. The collar 9 is provided with radial arms 12 pivoted at 13 to 85 operating rods 14, the arms 12 being diametrically opposite one another. The rods 14 are pivoted at 15 to ears 16 of an enlargement or shoulder 17 of a rifle bar 18.

Now referring more particularly to Figs. 90 6 to 9 inclusive, the feed cylinder 4 shown therein is surrounded by a spur gear 19 which is housed in the jacket 8 and which is fastened to the feed cylinder 4 by a pin, screw or the equivalent 20. The gear 19 and 95 bearings 7 prevent end play of the feed cylinder 4.

The spur gear 19 meshes with a spur gear 21 which is provided with internal ratchet teeth 22 that are adapted to be engaged by 100 pawls 23 pivoted at 24 in an enlargement or shoulder corresponding to the enlargement or shoulder 17 in Fig. 2 and designated by the same reference character, said shoulder being formed on a stem corresponding to the 105 stem 18 in said figure and designated by the same reference character. In the instance shown there are two pawls 23 and each pawl is normally pressed outward into engagement with the appropriate ratchet tooth by 110 a pin 25 working in a recess 26, said pin being pressed outward by a coil spring 27

seated in the recess. When the enlargement 17 is rotated clockwise in Fig. 7 it turns the spur gear 21 clockwise so as to operate the spur gear 19 counterclockwise, thereby turning the feed cylinder 4 and the drill steel 3 counterclockwise. When the enlargement 17 is turned counterclockwise the pawls 23 slip over the ratchet teeth 22 as is readily understood so that the feed cylinder and 10 drill steel will not be turned.

The upper and lower faces of the enlargement 17, see Fig. 6, are preferably engaged by wear plates 28, which plates prevent end play of the rifle bar 18.

15 Now referring again to the drawings of both embodiments of the invention the rifle bar 18 is journaled adjacent the shoulder 17 by upper and lower bearings 29, 30 of the jacket 8, the shoulder 17 and bearings 29, 30 20 in Fig. 2 preventing end play of the rifle bar. The rifle bar is provided with a helical groove or with helical grooves 31 which engage a helical tongue or tongues 32 in a bushing 33 of a plunger 34, said bushing 25 being screw-threaded into the upper end of the plunger and extending for but a portion of the length of said plunger which is hollow to accommodate the rifle bar 18 when the plunger moves on its up-stroke.

30 The plunger 34 works in a cylinder 35 and is provided with a splineway 36 engaged by a spline 37 which projects inward from the cylinder wall so as to prevent relative turning between said plunger and the 35 cylinder. It is clear that, owing to the foregoing described construction, if the plunger 34 be reciprocated it will cause, in Figs. 2 to 5 inclusive, oscillation of the collar 9 which in turn will cause the feed cylinder 4 to oscillate so as to turn the drill steel 3. In Figs. 6 to 9 reciprocation of the plunger 34 will rotate the spur gear 19 step by step so as to transmit a step by step movement 40 in one direction to the feed cylinder and drill 45 steel, upward movement of the plunger producing the movement and downward movement of said plunger being ineffective to produce reverse movement of the drill steel on account of the pawls 23 slipping over the 50 ratchet teeth 22.

The jacket 8 is provided with a suitable handle 38 whereby the operator will aid in steadyng the drilling machine during the drilling operation.

55 Means are provided to admit compressed fluid alternatively on opposite sides of the plunger 34 so as to reciprocate said plunger to cause the hereinbefore described oscillatory or step by step rotary movements, as 60 the case may be, of the drill steel 3 and said means will now be described. The cylinder 35 is provided adjacent its ends with ports 39, 40 connected by ducts 41, 42 respectively with any suitable valve mechanism *a* such, 65 for instance, as that already known in the

pneumatic tool art and shown in the drawings, but not described in detail herein since it forms no part of this present invention. The cylinder 35 is also provided with ports 43, 44 positioned so as to be opened when 70 the plunger 34 is at or near the end of its up stroke and down stroke respectively. These ports 43, 44 are connected by ducts 45, 46 respectively to the valve mechanism *a* so as to cause shifting thereof in a manner 75 well understood to alternatively admit operating fluid through the ports 40, 39 to the cylinder 35 to first move the plunger downward and then upward so as to oscillate the rifle bar 18, to thereby produce oscillation of 80 the drill steel in the form of the invention shown in Figs. 2 to 5, and to thereby produce step by step rotation in one direction of the drill steel in the form of the invention shown in Figs. 6 to 9 inclusive as described 85 hereinbefore in detail.

Assuming that the parts are in the positions shown in Figs. 2 to 5 inclusive, it is clear that the compressed air or other operating fluid will flow from the valve device *a* 90 through the port 39 so as to force the plunger 34 upward to turn the collar 9 in the direction of the arrow *b*, Fig. 4, thus to turn the feed cylinder 4 and thereby turn the drill steel 3 to the left in Fig. 1.

95 When the plunger 34 reaches the end of its up stroke it uncovers the port 43 so as to admit compressed fluid from the cylinder 35 through the duct 45 to the valve device to operate it in a manner well understood 100 in the art to cut off the air supply from the duct 41 and to supply air through the duct 42 to the upper end of the cylinder 35 to drive the plunger 34 on its down stroke and thereby turn the collar 9 in a direction opposite to that indicated by the arrow *b* to thereby turn the drill steel to the right in Fig. 1.

105 The valve device *a* thus continues to alternatively admit air to opposite sides of the plunger 34 so as to oscillate the feed cylinder 4, the oscillations of said feed cylinder being transmitted to the drill steel 3 so as to produce the desired changes in the 110 relation of the cutting edges to the surfaces acted on by the drill steel.

115 In Figs. 6 to 9 inclusive, assuming that the parts are in the positions shown in said figures, it is readily understood from the hereinbefore described operation of the 120 form of the invention shown in Figs. 2 to 5 inclusive, that the plunger 34 has just completed its up-stroke for causing turning of the drill steel to the left in Fig. 1, that the next stroke of said plunger will be down 125 and that during said down stroke the pawls 23 will slip over the ratchet teeth 22, and that during the next succeeding up-stroke of the plunger the drill steel 3 will be given further rotation to the left. Thus successive 130

up-strokes of the plunger 34 will produce step by step rotation of the drill steel in one direction.

It is noted that the body of the drilling machine is turned, instead of the chuck as in prior patented devices. The advantage of turning the body of the drilling machine instead of just the chuck is that in event of a relatively long drill steel being employed 10 to drill a hole horizontally or approaching a horizontal the drill steel will tend to cause tilting of the chuck within its bearing member and consequently cause binding between the bushing and said bearing member if the 15 chuck itself be rotated, but if the body itself of the drilling machine be turned, as in this invention, such binding does not occur. Applicant's construction for this reason is especially preferable to the old construction 20 in stoping machines when drilling at a considerable angle to the vertical, in such stoping machines the feeding mechanism be-

ing connected directly to the body of the drilling machine.

I claim:

1. The combination with the body of a drilling machine, of rods pivotally connected with said body, and means to reciprocate said rods to oscillate the body.

2. The combination with the body of a 30 drilling machine, of a cylinder, a plunger in said cylinder, means to prevent turning of the plunger, means to alternatively admit an operating fluid on opposite sides of the plunger, a rifle bar oscillated by reciprocation of the plunger, and a rod pivotally connected with the rifle bar and body of the 35 drilling machine.

Signed at Los Angeles, California, this 19th day of December, 1916.

CHARLES A. HULTQUIST.
